UNITED STATES PATENT OFFICE.

ANTONY SZABADOS, OF NEW MICHEL, BRITISH COLUMBIA, CANADA, ASSIGNOR OF
ONE-HALF TO HELENA MUELLER, OF NEW MICHEL, CANADA.

WRENCH.

1,025,431.

Specification of Letters Patent.

Patented May 7, 1912.

Application filed October 6, 1911. Serial No. 653,141.

To all whom it may concern:

Be it known that I, ANTONY SZABADOS, a subject of the King of Hungary, residing at New Michel, Province of British Columbia, Canada, have invented certain new and useful Improvements in Wrenches, of which the following is a specification, reference being had therein to the accompanying drawings.

10 This invention relates to wrenches, and the objects of my invention are to furnish a wrench with an adjusting mechanism that is protected and not liable to injury by ordinary use, and to provide a wrench with an 15 adjustable jaw that can be easily and quickly shifted and positively locked in an adjusted position.

With the above and other objects in view, the invention resides in the novel construction, combination and arrangement of parts to be hereinafter specifically described and then claimed.

Reference will now be had to the drawing, wherein:—

25 Figure 1 is a side elevation of a wrench in accordance with this invention, Fig. 2 is a vertical transverse sectional view of a portion of the wrench, Fig. 3 is a cross sectional view of a portion of the wrench, and Fig. 4 30 is a horizontal sectional view of the wrench taken on the line X—X of Fig. 3.

A wrench in accordance with this invention comprises a channel-shaped handle 1 having a longitudinal channel 2 extending 35 from a point in proximity to the lower end of the handle to the upper end thereof, and the upper end of the handle terminates in a fixed jaw 3 having a gripping surface 4. The handle 1, adjacent to the jaw 3, has an 40 off-set portion 5 providing a recess 6 that is in communication with the channel 2. This recess and the channel 2 are adapted to be closed by a face plate 7 suitably secured to the walls of the handle 1.

45 Slidably mounted in the channel 2 against the face plate 7 is a shank 8 having the upper end thereof provided with a jaw 9 having a gripping surface 10 confronting the gripping surface 4 of the jaw 3 and co-operating 50 therewith in gripping a nut or other structure having flat sides or facets. The shank 8 has a longitudinal slot 11, for a purpose that will presently appear.

Journalized in the walls of the recess 6 are 55 transverse shafts 12 and 13 and upon these

shafts are arranged a train of gears, comprising a small gear wheel 14 carried by the shaft 12, a large gear wheel 15 mounted upon the shaft 12 and meshing with a small gear wheel 16 mounted upon the shaft 13, 60 and a large gear wheel 17 carried by the shaft 13 and meshing with a rack 18 provided therefor upon the shank 8 at one side of the slot 11.

The walls of the handle 1 and plate 7 are 65 provided with oppositely disposed bosses 19 and slidably mounted in these bosses is a push rod 20 having a rack 21 meshing with the small gear wheel 14. The push rod 20 has the outer end thereof provided with a 70 button 22, and at a point approximately intermediate the ends thereof, said push rod has an arm 23 engaged by a flat spring 24, secured, as at 25 to the inclined lower wall of the recess 6. This spring normally maintains the push rod in an extended position with the shank 8 lowered in the handle 1. The push rod 20 extends through the slot 11 and an inward movement of said rod actuates the train of gears to move the shank 8 80 upwardly in the handle, thereby moving the jaw 9 away from the jaw 3.

To lock the shank 8 in an adjusted position, a push pin 26 is employed. This pin is slidably mounted in bosses 27 and 28, carried by the walls of the handle 1 and plate 7 and said pin, intermediate the ends thereof, has an arm 29 provided with teeth adapted to engage the rack 18 and hold the shank 8. The arm 29 is normally maintained in engagement with the rack 18 by a small compression spring 30 arranged within the boss 28 and pressing against the inner end of the push pin, while the outer end of the push pin has a button 31 to facilitate pushing the 95 pin inwardly to release the shank 8.

It is thought that the operation and utility of the wrench will be apparent without further description, and while in the drawing there is illustrated a preferred embodiment of the invention, it is to be understood that the structural elements thereof are susceptible to such variations and modifications as fall within the scope of the appended claims.

100 What I claim is:—

1. A wrench of the type described, comprising a channel handle, a jaw carried thereby, a shank slidably mounted in said handle, a jaw carried by the upper end of 110

said shank, a rack carried by said shank within said handle, a train of gears arranged in said handle and adapted to move said shank, a push rod arranged in said handle 5 and adapted to actuate said train of gears, and means arranged in said handle and adapted to lock said shank in an adjusted position.

2. A wrench comprising a channel handle, 10 a face plate carried thereby, a jaw carried by the upper end of said handle, a slotted shank slidably mounted in said handle, a jaw carried by the upper end thereof, a rack carried by said shank, a train of gears ar-

ranged within said handle and adapted 15 when actuated to move said shank, a spring pressed push rod arranged in said handle and adapted to actuate said train of gears, a push pin arranged in said handle, and an arm carried by said pin within said handle 20 and adapted to lock said shank in an adjusted position.

In testimony whereof I affix my signature in the presence of two witnesses.

ANTONY SZABADOS.
